UNITED STATES PATENT OFFICE.

ROY C. WILLIAMSON, OF KENNETT SQUARE, PENNSYLVANIA, ASSIGNOR TO AMERICAN ROAD MACHINERY COMPANY, INC., OF KENNETT SQUARE, PENNSYLVANIA, A CORPORATION OF DELAWARE.

POWER LIFT FOR ROAD MACHINES.

Application filed September 18, 1925. Serial No. 57,061.

My invention relates to road machines and more particularly to power operated machines for scarifying and grading roads. Machines of this kind have been heretofore made, with power applied to the rear axle, through a Fordson or similar power unit mounted on the machine frame whereby the machine is propelled. There is a transversely extending bar carrying scarifiers and also a scraping or levelling blade hung from the machine frame, and adapted to be raised or tilted at an angle or thrown out of action entirely, by hand levers and connections from the operator's seat or platform.

It will be understood that the operator of a road machine of this kind has two distinct and separate things to take care of. First, he has to run his engine and steer the machine in the direction and path to be acted upon, faster or slower as the work may require. At the same time he has to attend to the lowering, tilting and raising out of action of the scarifiers and scraper.

The object of my invention is to provide a road machine of this description wherein these raisings and lowerings and tilting adjustments of both scarifiers and scraper may be operated by power from the engine which is at the same time propelling the vehicle.

Thus the manual labor falling upon the operator is greatly lessened and he can devote more time and attention to the operation of the various adjustments, insuring better work done by the machine and better time in doing it.

I will now proceed with a detailed description of a road machine having my invention applied thereto, with reference to the accompanying drawings, in which—

Fig. 1 is a side view of a road machine embodying my invention, partly in section, and showing a Fordson power unit in broken lines.

Fig. 2 is a plan view of a portion of the same, drawn to an enlarged scale.

Fig. 3 shows a cross-section, slightly enlarged, on the line 3—3 of Fig. 1.

Fig. 4 is an enlarged detail of construction shown principally in section.

The frame *a* of the machine, carried upon the wheels *b*, has mounted on it a motor shown as a Fordson *c*. The driving axle *d* of the Fordson imparts motion to the driving axle

e of the machine by sprockets and belt *f* in the usual manner. 55

The cranking shaft on the front of the Fordson is utilized to transmit power for manipulating the scarifier and scraper, and provision for cranking the motor at starting is provided by the regular side shaft take-off 60 indicated at *g*, Fig. 2.

The front cranking shaft is connected by a suitable coupling *h* with an extension carrying a worm *i* meshing with a worm wheel *j* turnable upon a cross shaft *k* mounted in 65 bearings on the machine frame.

Shaft *k* carries a standard form of clutch *l*, by means of which worm wheel *j* is caused to drive shaft *k* when desired. The clutch is operable by means of levers and links *m* connecting with a rod *n* which extends rearwardly to a hand lever, not shown, convenient to the operator. 70

Slidably splined on shaft *k* is a member having two conical friction wheels *o* facing 75 toward each other. A longitudinally extending shaft *p* carries a similar conical friction wheel *q*, projecting intermediate wheels *o* in such manner that when the member carrying wheels *o* is slid along shaft *k*, frictional contact is made between wheel *q* and either one or the other of wheels *o*, whereby shaft *p* may be driven in either direction. 80

As seen in Fig. 2, the member carrying wheels *o* may be operated by means of bell crank lever *r* connected with reach rods *s*, which extends rearwardly and is connected with a hand lever, not shown, convenient to the operator. 85

Shaft *p* is mounted at its forward end in 90 a suitable bearing *t* and carries a worm *u*, which meshes with a worm wheel sector *v* on a cross shaft *w* mounted in bearings on the machine frame.

Shaft *w* carries at either end arms or cranks 95 *x* which are pivotally connected by links *y* with the scarifier frame *z*. Frame *z* is suspended at both ends by bars *z* pivotally hung from the side members of frame *a*. Thus, in Fig. 1, when shaft *p* is turned by friction 100 wheels *o—q*, the motion is transmitted to shaft *w*, arms *x* are turned, and the suspended scarifier bar is swung forward and upward.

The usual scarifiers *6* are clamped to frame *z* by individual blocks and bolts *7* and are 105 thus raised or lowered by the operator,

through reach rod *s*, moving the friction wheel member *o* in one direction or the other.

The scraper bar 8 is fixedly carried by suitable links from brackets 9 depending 5 from a ring 10, carried in turn by a swinging frame 11, by means of a central pivot 12. Thus, the ring or circle and scraper bar carried by it may be turned about pivot 12 in a horizontal plane. The circle is provided with a series of holes 13, and after the scraper bar has been turned to the desired angle a bolt 14 is dropped through a hole provided for it in frame 11 and the hole 13 which aligns with it, and thus the circle and scraper 10 bar are held in their angular position with respect to frame 11. Depending angles 15, from frame 11, underlie portions of circle 10, and the angle which underlies bolt 14 is provided with a hole, in line with the hole in frame 15 20 25 30 35 40 45 50 55 60 65 70 75 80 85 90 95 100 105 110 115 120 125 130 member 40 of the machine frame. Thus the frame may be swung from side to side about pivot 17, up or down about pivot 16, and may be swivelled by means of pivot 18.

Frame 11 at its forward end carries a cross-bar 19, both ends of which are supported by rods 20 depending from arms 21 of worm sectors 22, mounted in brackets 23 on both side 35 members of frame *a*. In these brackets are also mounted short vertical shafts carrying worms 24 in mesh with worm sectors 22, and at its lower end each shaft carries a conical friction wheel 25.

Friction wheel 25, on each side of the machine, is arranged to be driven in either direction by a slideable member having two conical friction wheels 26, in a similar manner to the before-described friction wheels *q* and *o*. Each of these slideable members is splined to a horizontal shaft 27, which extend forward and are arranged to be driven from cross shaft *k* by means of bevels 28. The slideable members carrying the friction cones 26 are individually movable from a central position in which they do not contact with cone 25, either backward or forward, by means of yoke arms 29, which are connected by reach rods 30 with hand levers 31 arranged 55 60 65 70 75 80 85 90 95 100 105 110 115 120 125 130 convenient to the operator. By operating one of these hand levers, therefore, when the engine is running and clutch *l* is thrown in mesh to drive shaft *k*, the operator can at will cause the vertical shaft carrying worm 24, on either side of the machine, to rotate in either direction, thus raising or lowering that end of bar 19 on frame 11 and with it that end of the scraper bar, which movement is allowed by the swivelling of yoke 18 in cross member 40.

The following provision is made for maintaining the scraper bar in any set position sideways, whether it is desired to run with the scraper central or projecting one side or the other.

Crossbar 19 of frame 11 has rigidly secured to it a guide bar 33 having a series of holes 34. A slide 35 is mounted upon bar 33 and carries a spring-pressed pin 36, in line with holes 34, whereby the slide may be definitely located at various points along the bar. A swinging rod 37 connects slide 35 with a crossbar 38 connecting the two side members of frame *a*.

As shown in the drawings, the scraper is shown in center position. By withdrawing pin 36 free of bar 33, bar 17 and frame 11 may be swung to one side, bar 33 sliding in slide 35, and pin 36 allowed to enter another hole 34, holding the swinging frame 11 and scraper 80 85 90 95 100 105 110 115 120 125 130 carried thereby in set position.

The front wheels of the machine are mounted upon steering knuckles (not shown) which are connected in the usual manner and may be actuated as by a rod 41 with an arm 42 on a post 43, at the other end of which is another arm 44 from which a reach rod 45 extends rearwardly where it is connected with the steering post 46 of the Fordson by bevel gears or other means, not shown as it involves no 95 invention.

Having now fully described my invention, what I claim and desire to protect by Letters Patent is:

1. A road machine having a frame with supporting wheels, a motor on the frame, means for driving the machine by the motor, a road working tool pivotally mounted on the frame, a transverse shaft on the frame, cranks on the shaft, connections between the cranks and the tool, a worm and worm wheel connection for rotating the shaft, and clutch means for connecting the said shaft to the motor for raising or lowering the tool.

2. A road machine having a frame with supporting wheels, a motor on the frame, means for driving the machine by the motor, a road working tool pivotally mounted on the frame, a transverse shaft on the frame, cranks on the shaft, connections between the cranks and the tool, a transverse power shaft, a worm wheel on the first shaft, a longitudinally extending shaft having a worm thereon meshing with the worm wheel, shifttable friction cones on the transverse power shaft, a friction cone on the longitudinal shaft arranged to be engaged by either of friction cones, and clutch means for connecting the power shaft to the motor.

3. A road machine having a frame with supporting wheels, a motor on the frame, means for driving the machine by the motor, a road working tool pivotally mounted on the frame, a transverse shaft on the frame, cranks on the shaft, connections between the

cranks and the tool, a transverse power shaft, a worm wheel on the first shaft, a longitudinally extending shaft having a worm thereon meshing with the worm wheel, shiftable friction cones on the transverse power shaft, a friction cone on the longitudinal shaft arranged to be engaged by either of friction cones, a worm wheel free to rotate on the power shaft, a motor shaft, a worm on the 10 motor shaft meshing with the last mentioned worm wheel, and a clutch for connecting the last mentioned worm wheel to the power shaft.

4. A road machine having a plurality of 15 tools mounted thereon, a motor, a transverse power shaft and two longitudinal power shafts geared thereto, a worm and worm wheel connections including a clutch between the motor and transverse shaft, connections 20 between each of the longitudinal power shafts and one of the tools, and a clutch between each of said longitudinal power shafts and said tool.

5. A road machine having a plurality of 25 tools mounted thereon, a motor, a transverse power shaft and two longitudinal power shafts geared thereto, a worm and a worm wheel connection including a clutch between the motor and transverse shaft, adjusting 30 connections between the longitudinal power shafts and one of the tools including shiftable friction cones, whereby the tool may be moved in either direction, and means for shifting either of said cones to raise or lower 35 one end of the tool independent of the other end.

6. A road machine having a frame with supporting wheels, a motor on the frame, means for driving the machine by the motor, 40 a road working tool pivotally mounted on the forward end of the frame, a transverse shaft on the frame, crank and link connections between the shaft and tool, a longitudinal shaft journaled on the frame, worm and worm 45 wheel connections between said shafts, and means for connecting said longitudinal shaft to the motor.

7. A road machine having a frame with supporting wheels, a motor on the frame, means for driving the machine by the motor, 50 a road working tool pivotally mounted on the forward end of the frame, a transverse shaft on the frame, crank and link connections between the shaft and tool, a longitudinal shaft journaled on the frame, worm and worm 55 wheel connections between said shafts, a second transverse shaft mounted on the frame,

means for driving the second transverse shaft by the motor, and a friction clutch connection between the second transverse shaft and the longitudinal shaft arranged to rotate the longitudinal shaft in either direction when the second transverse shaft is actuated by the motor. 60

8. A road machine having a frame with 65 supporting wheels, a motor on the frame, means for driving the machine by the motor, a transverse power shaft journaled on the frame, means for driving the power shaft from the motor, a plurality of longitudinal 70 shafts journaled on the frame, gearing connecting said last mentioned shafts with the power shaft, a road working tool pivotally connected to the frame of the machine, crank and link connections between opposite sides of said tool and the frame, and actuating connections between each of said crank and link connections and one of the longitudinal 75 shafts including means for actuating said crank and link connections in either direction when the longitudinal shafts are driven. 80

9. A road machine having a frame with supporting wheels, a motor on the frame, means for driving the machine by the motor, 85 a road working tool pivotally mounted on the frame, a sector pivotally mounted on each side of the frame, crank and link connections between each sector and one side of the road working tool, a worm shaft on each side of the frame having a worm cooperating with its sector, and means for connecting said worm 90 shafts with the motor.

10. A road machine having a frame with supporting wheels, a motor on the frame, means for driving the machine by the motor, 95 a road working tool pivoted to the frame, a worm sector pivotally mounted on each side of the frame, a crank and link connection between each sector and one side of the road working tool, a vertical worm shaft journaled 100 on each side of the frame, each having a worm meshing with its sector, a cone clutch member on the end of each shaft, a longitudinal shaft on each side of the frame, each of said shafts having two clutch elements arranged to be shifted into engagement with a clutch element on one of the worm shafts, means for shifting said last mentioned clutch elements, and means for driving said shafts from the motor. 105

In testimony of which invention, I have hereunto set my hand, at Kennett Square, Penna., on this 10th day of September, 1925.
ROY C. WILLIAMSON.
